UNITED STATES PATENT OFFICE.

SILAS S. SEE, OF ROANOKE, VIRGINIA.

WOOD-CUTTING MACHINE.

Application filed May 2, 1921. Serial No. 466,006.

To all whom it may concern:

Be it known that I, SILAS S. SEE, a citizen of the United States, residing at Roanoke, in the county of Roanoke and State of Virginia, have invented certain new and useful Improvements in Wood-Cutting Machines; and I do hereby declare the following to be a full, clear, and exact description of the invention, such as will enable others skilled in the art to which it appertains to make and use the same.

This invention relates to machines for cutting openings in wooden or other stock, and is primarily designed for rapidly and accurately cutting arcuate openings, such for instance as hand holes as are commonly provided in the ends of crates.

A further object of the invention is to provide for the convenient insertion and removal of the work-piece with respect to a work-holder, and also to provide for the convenient manipulation of the work-holder to move the latter towards and away from the cutting tool as well as to swing the work piece with respect to the cutting tool so as to produce an arcuate opening in the work-piece.

With these and other objects in view, the present invention consists in the combination and arrangement of parts as will be hereinafter more fully described, illustrated in the accompanying drawings and particularly pointed out in the appended claims, it of course being understood that changes in the form, proportion, size and minor details may be made, within the scope of the claims, without departing from the spirit or sacrificing any of the advantages of the invention.

40 In the drawings:

Figure 1 is a side elevation of a machine embodying the features of the present invention.

Figure 2 is a sectional elevation on the line 2—2 of Figure 1.

Figure 3 is an irregular vertical sectional view on the line 3—3 of Figure 2.

Figure 4 is a detail sectional view on the line 4—4 of Figure 2.

50 Figure 5 is a view similar to Figure 1 showing another embodiment of the means for moving the work-holder towards and away from the cutting tool.

Figure 6 is a cross sectional view on the line 6—6 of Figure 5.

The embodiment of the present invention, as shown in the accompanying drawing, includes a frame or support for the working parts of the machine, said frame or support including a bed 1 and leg standards 2. As best shown in Figures 2 and 6 of the drawings it will be seen that the bed 1 is of channel formation in cross section and has inwardly directed guide rails 3 at the tops of the upstanding side flanges of the channel section bed. These guide rails 3 define a guideway in which works a work-holder consisting of a carriage 4 in the form of an upright plate having a substantially horizontal base 5 projecting at one side only thereof and shaped at its opposite longitudinal edges to engage and slide upon the guide rails 3, as clearly shown in Figure 2 of the drawings. Disposed centrally upon the bottom of the base 5 is a longitudinal rack 6 meshing with a pinion 7 mounted upon a rock shaft 8 extending across the bed 1 and journaled in the upright flanges thereof, whereby the carriage may be moved back and forth upon the bed in a manner as will be hereinafter more fully described.

Mounted to oscillate upon a horizontal axis and disposed in front of the upright carriage portion 4 is a work-holder 9 in the form of a flat plate pivotally supported near its lower edge and midway between the opposite upright edges upon a suitable pivot 10, preferably in the form of a bolt as clearly indicated in Figure 3.

For the guidance of the work-holder 9 in its oscillatory movement about the pivot pin 10, said work-holder is provided with a pin or post 12 having its head 13 countersunk in the front face of the member 9 so as to lie flush therewith. The shank of the pin 12 is received within an arcuate slot 11 formed in the part 4 of the carriage and struck from the pivot 10 as a center. A suitable nut 14 is provided upon the rear end of the pin or post 12 so as to hold the latter against endwise displacement and to enable convenient insertion and removal of the pin.

Disposed across the front of the work-holder 9 just above the bottom edge thereof is a cross head 15 through which the bolt

10 passes, suitable fastenings 16 being employed to rigidly secure the cross-head to the part 9. Upstanding spring clips or fingers 17 are disposed in front of the work-holder 5 and are secured thereto at their lower ends by fastenings 18 and 19, the fastenings 18 entering the cross head 15 and the fastenings 19 extending through blocks 20 which are in turn secured to the work-holder 9 by the 10 fastenings 19. The spring clips or fingers 17 are spaced in front of the work-holder 9, as best indicated in Figure 3 of the drawings, and the upper end of each clip is flared or bent outwardly away from the work-holder.

15 The cross-head 15 projects a suitable distance beyond each upright edge of the work-holder 9, and upon one projecting end there is an adjustable abutment 21 rising above the cross-head and provided with an eye 20 portion 22 through which the cross-head is received. A suitable set screw 23 is carried by the bottom of the abutment and enters the eye for engagement with the cross-head to adjustably fix the abutment upon the 25 cross-head. The opposite end of the cross-head is provided with a suitable handle 24, and at the inner side of the handle there is provided another abutment 25 having an eye portion 26 receiving the cross-head and 30 a set screw 27 to adjustably fix the abutment upon the cross-head. A cam 28 is pivotally mounted, as at 28', upon the abutment 25, preferably in a slot therein so that the edge of the cam may work through the 35 open side of the slot in the inner face of the abutment, the handle portion 29 of the cam projecting outwardly through the opposite open end of the slot and into position for convenient operation and adjacent the handle 24.

40 The work-piece, which has been designated 30 is placed downwardly in the work receiving seat or socket defined by the work-holder plate 9, the cross-head 15, the abutments 21 and 26 and the spring clips or fingers 17. The work-piece rests at its bottom edge upon the cross-head 15 and at its opposite upright edges against the abutments 21 and 26 which have been previously 45 adjusted upon the cross-head to an approximate fit for the work-piece, the cam 28 being afterwards manipulated to bear against the adjacent edge of the work-piece and snugly clamp the latter between the cam 50 and the opposite abutment 21, whereby the work-piece is snugly held upon the work-holder.

55 In front of the work-holder is a suitable rotary cutting tool 31 mounted upon a rotatable shaft or spindle 32 journaled in spaced bearings 33 provided upon a substantially U-shaped bracket 34 rising from the top of the bed 1, there being a suitable driving pulley 35 mounted upon the spindle

or shaft 32 and located between the bearings 33.

60 One form of means for rocking the rock shaft 8 for moving the carriage towards and away from the cutting tool, has been shown in Figures 1 and 2 and includes an upstanding lever 36 fixed between its ends upon one end of the rock shaft 8 at the outer side of the bed 1 and adjacent the handle 24. The upper end of the lever is provided with a weight 37, and its lower end is pivotally 65 connected at 38 to a link or rod 39 which is mounted to slide endwise through an oscillating eye or guide 40 pivotally mounted upon the bed 1 upon a suitable pivot which has been designated 41 in Figure 2 of the drawing. Adjustable stops 42 and 43 are provided upon the link or rod 39 at opposite sides of the guide 40 for successive contact with the latter to limit the swinging movements of the lever 36 and thereby limit the 70 oscillatory movement of the pinion 7. As the pinion 7 is in mesh with the rack 6, the carriage 4 may be moved back and forth upon the bed by the manipulation of the lever 36.

75 In using the machine, as shown in Figures 1 to 4, the lever 36 is swung to its right hand limit so as to move the work-holder away from the cutting tool 31, whereupon the work-piece 30 is introduced into the work-holder and snugly clamped therein by manipulation of the clamping device formed by the cam 28. With the work-piece thus 80 rigidly held upon the work-holder, the lever 36 is slowly swung to the left so as to move the carriage towards the rotary cutting tool 31 and to bring the work-piece into engagement with the tool, the handle 24 of the work-holder being manipulated to swing the work-holder upon its pivotal axis 10 85 for the purpose of cutting an arcuate opening in the work-piece, such opening being shown at 44 in Figure 2 of the drawing. After the completion of the opening, the carriage and the work-piece are backed 90 away from the tool by moving the lever 36 to the right, after which the clamp 28 may be released, the work-piece removed, another work-piece inserted and the operations 95 repeated to produce an arcuate opening in the new work-piece. It will now be understood that the parts 40, 42 and 43 constitute a stop to limit the slidable movements of the carriage in opposite directions, thereby obviating loss of time in moving the carriage an unnecessary distance from the tool and also preventing the tool from 100 engaging the work-holder 9 and injuring the latter and the tool.

105 In the form of the machine shown in Figures 1 and 2, hand manipulation of the lever 36 is required to move the carriage towards the cutter 31, but this movement of

the carriage may be accomplished by foot actuated means, such for instance as has been shown in Figures 5 and 6 of the drawings, wherein 45 designates a link or rod depending from the gear or pinion 7 upon which it is pivotally hung as at 45'. The lower end of the link is pivotally or loosely connected to a treadle 46 by means of any suitable connection, as for instance a hook or eye 47 disposed about midway between the ends of the treadle. This treadle extends transversely beneath the bed of the machine, adjacent the floor and in convenient reach of a foot of the operator. The rear end of the treadle is fulcrumed as at 48 upon a rod or bar 49 hung from the bed 1. Any suitable form of connection between the rod and the bed may be employed, such as by having the upper end of the rod or bar threaded and passed through an opening in the inwardly directed bottom flange 50 of the bed, there being nuts 51 provided upon the threaded end of the bar above and below the flange and set tightly 25 thereagainst. The front portion of the treadle is guided upon an upright rod or bar 52 depending from the other inturned flange of the bed and secured thereto in the manner described for rod 49. The rod 52 passes through a slot 53 extending longitudinally of the treadle, and adjustable abutments 54 and 55 are provided upon the bar above and below the treadle. The adjustable abutments may be in the form of 30 collars having set screws as clearly shown in the drawings and are intended to limit the up and down movements of the treadle and in turn limit the back and forth movements of the carriage in the manner of the 35 parts 40, 42 and 43 shown in Figure 1 of the drawings.

Normally the treadle is at its upper limit in engagement with the upper stop 54, and is yieldably held in this position by means 45 of a contractile spring 56 anchored or secured at one end to the bed of the machine as indicated at 57, the other end of the spring being provided with a rod or link 58 pivotally connected to the gear or pinion 7 50 at a point below the horizontal axis thereof.

With the arrangements shown in Figures 5 and 6, the operator or attendant may actuate the treadle 46 with one foot so as to rotate the gear 7 and feed the work towards 55 the cutter 31, thereby leaving both hands free for any other operations that may be necessary or desirable.

Each form of carriage feeding means includes a tension device for yieldably maintaining the carriage at the limit of its travel away from the cutter thereby requiring a 60 manual manipulation to feed the carriage towards the cutter, the tension device automatically returning the carriage to its original position just as soon as the operator re-

moves pressure from the lever 36 in one instance and the treadle 46 in the other instance.

From the foregoing description, and as shown in the drawing, it will be readily understood that the machine of the present invention embodies few parts, all of which are readily accessible for assemblage, replacement and repairs, and the parts are so arranged that the work-piece may be conveniently and quickly fitted in place and removed, and the carriage together with the oscillatory work-holder are at all times under the convenient control of the attendant. The depth of the cut in the work-piece may be regulated by adjustment of the stop 43 so as to limit the forward travel of the carriage towards the rotary cutter 31, so that after the stop has once been adjusted, the attendant merely moves the lever 36 75 gradually towards the cutter until the movement is stopped by the stop 43 coming into contact with the guiding abutment 40.

In the construction shown in Figures 5 and 6, the depth of the cut in the work-piece may be regulated by adjustment of the stop 55 so as to limit the downward movement of the treadle and the forward travel of the carriage towards the rotary cutter 31, so that after the stop has been 90 adjusted the attendant merely presses his foot downwardly upon the treadle so as to gradually move the carriage towards the cutter until the movement of the treadle is stopped by the stop 55. Upon removing the 95 foot from the treadle the spring returns the treadle and consequently the carriage to its original position.

What is claimed is:

1. In a machine for cutting arcuate openings such as hand holes in stock, a rotary cutting tool mounted in relatively fixed position, a carriage movable toward and away from said tool axially thereof, a pivoted work holder on the carriage capable of oscillation in a plane at right angles to the axis of the tool, and means whereby the work holder may be moved for moving the work with respect to the tool. 105

2. In a machine for cutting arcuate openings such as hand holes in wooden or other stock, a stationary frame, a rotary cutting tool mounted in fixed relation with respect to the frame, a carriage slidably mounted upon the frame for movement longitudinally thereof and of the axis of the tool, a work-holder pivoted on the carriage at a point eccentric with respect to the axis of the tool and capable of oscillation in a plane at right angles to the axis of the tool, means for moving the carriage, and means for swinging the work holder. 110

3. In a machine for cutting arcuate openings such as hand holes in wooden or other stock, a frame, a horizontally disposed ro- 120

tary cutting tool mounted in relatively fixed position with respect to the frame and above the same, a carriage slidably mounted upon the frame for movement in a horizontal direction toward or from the tool, means for moving the carriage, a work holder on the carriage pivoted thereon at a point eccentric

with respect to the axis of the tool, the work holder being capable of limited swinging movement in a vertical plane at right angles ¹⁰ to the axis of the tool.

In testimony whereof I affix my signature.

SILAS S. SEE.
